FILE GUARDS

Cornelius F. Hoyt, Rochester, N. Y.

Application November 3, 1954, Serial No. 466,524

7 Claims. (Cl. 29—80)

This invention relates to a file guard and more particularly to a flexible guard adapted for use with files used for example in automobile body repairing.

In automobile body repairing, the fenders and body parts requiring straightening are brought back to approximate shape, and the outer surface thereof filled with body solder, and thereafter the surface is rendered smooth through the use of a body file having a relatively flat surface with coarse transverse cutting teeth. Such files are relatively flexible, and are adapted through the use of a file holder to be curved lengthwise thereof, either concave or convex, to assist in smoothing out curved surfaces. The width of such files is in order of about an 1 1/4", and so long as the file is held generally flat against the work, no difficulty is encountered. However, when a fender has been rounded out and filled with solder, and a finished surface nearly completed for applying enamel or lacquer, there is always danger that in stroking the file, the same may be tipped, with the result that the sharp cutting corners of each of the cutting teeth along the side edges of the file may gouge the work and ruin the nearly finished smooth surface. When so gouged, it is necessary to flow fresh solder on the surface and commence the smoothing operation anew, since the slightest groove will result in an unsightly line after the lacquer or enamel has been applied.

The present invention is directed to a guard for use in conjunction with such files, and holders therefor, which will effectively prevent accidental gouging. The invention is further directed to the provision of a guard which may flex lengthwise with the file, and which may also flex crosswise of the file so that the guard may be adjusted relative to the common plane of the cutting teeth of the file.

The above and other novel features of the invention will appear more fully hereinafter from the following detailed description, when taken in conjunction with the accompanying drawings. It is expressly understood that the drawings are employed for purposes of illustration only and are not designed as a definition of the limits of the invention, reference being had for this purpose to the appended claims.

In the drawings, wherein like reference characters indicate like parts:

Figure 1 is a side elevation of a file and holder with the guard in position;

Figure 2 is a top plan view of the file guard, the holder being cut away on the line 2—2 of Figure 1;

Figure 3 is a substantially full size transverse section taken on the line 3—3 of Figure 1, showing the application of the guard to a file and holder;

Figure 4 is a transverse section similar to Figure 3, in which the guard is adjusted to provide greater transverse curvature; and

Figure 5 is a section through the adjustment of the holder adapted to provide lengthwise curvature of the file

2

and guard, the section being taken on line 5—5 of Figure 1.

In Figure 1 there is shown a pair of spaced members 6 and 8 having hand grips 10 and 12, the members being connected by a resiliently flexible steel strap 14 and file 16, and an adjustable linkage comprising right and left hand threaded members 18 and 20 and a knurled sleeve 22 which comprise a turnbuckle 24. The threaded members 18 and 20 are pivotally attached to upstanding arms 26 and 28 of the respective members 6 and 8, and are pivoted thereto as at 30 and 32. The file and strap are secured to the members 6 and 8 by screws 34 and 36, the heads of which are countersunk in the file ends. The file has curved transverse cutting teeth 38 and 40, on its opposite sides, 15 which are milled or otherwise formed and subsequently hardened.

To prevent the edges 42 or 44 of the file from gouging the work, should the file be tipped during smoothing of a particular work piece, there is interposed between the file 16 and the strap 14, a channel section guard 46 formed of thin resilient steel, such as stainless steel or other suitable material. The ends of the guard are rounded as at 48 and 50, and the side edges are rolled lengthwise as at 52 and 54 to provide work-engaging flange faces 56 and 58, which will prevent tipping of the file during usage. The common plane of the faces 56 and 58 will lie slightly above the plane of the cutting teeth 38, so as not to interfere with the filing operation, and to permit the file to be used on slightly reverse curved work such as is indicated at 60 in Figure 3.

The guard is provided with matching holes at either end to receive the screws 34 and 36, and along either side, inward of the rolled edges 52 and 54 are series of enlarged 30 perforations 62 and 64 to provide adequate escape for filings.

In practice, the guard member will be provided with residual resilient transverse curvature as shown in Figure 4, which will permit the shifting of the plane of the rolled edges 56 and 58 with reference to the plane of the cutting teeth 38, by tightening or loosening the screws 34 and 36. In Figure 3, the screws are drawn tight, flattening the transverse curvature between the strap 14 and the file 16, whereas in Figure 4, the screws are "loosened," permitting slight transverse curvature whereby the rolled edges 56 and 58 substantially lie in the plane of the teeth. Any intermediate adjustment may be made as desired. In working convex surfaces as indicated at 62, the latter adjustment will be found desirable to afford adequate protection against tipping and possible gouging. The springiness of the guard member will hold the screws 34 and 36 taut, no matter whether in the "loosened" position of Figure 4 or when set as in Figure 3.

The turnbuckle 24 is adapted to bend the strap and file lengthwise to provide either convex or concave curvature, depending on whether the sleeve 22 is turned to draw the members 6 and 8 closer or to spread them. The flexibility of the guard member lengthwise, is such as to readily conform to whatever curvature is imposed on the file 16 and strap 14, and thus the guard readily accommodates itself to any of the usual adjustments intended to be made by the holder and file, were the guard not present. It will be seen thus that the guard is adaptable to protecting the work against accidental gouging at all times, and readily adaptable to be equally effective on surfaces being smoothed of varying curvature.

While stainless steel has been suggested for the guard, it will be appreciated that any tough resilient sheet metal having the desired characteristics may be used, it being necessary that the flange faces 56 and 58 be rounded and smooth so as not to mark or mar the surface being prepared.

Although a single embodiment of the invention has been illustrated and described, it is to be understood that the invention is not limited thereto. As various changes in the construction and arrangement may be made without departing from the spirit of the invention, as will be apparent to those skilled in the art, reference will be had to the appended claims for a definition of the limits of the invention.

What is claimed is:

1. A file guard comprising a resilient sheet metal elongated channel section, said channel section having a central portion with rolled edges along the side edges thereof, said guard adapted to be held against the back of an elongated flat rectangular section file, said guard being of a width approximately double the width of the file for which it is adapted, and said rolled side edges being of a diameter slightly less than the thickness of the file whereby a common plane tangential to said rolled edges lies behind the outer file surface.

2. A file guard comprising a resilient sheet metal elongated channel section, said channel section having a central portion with rolled edges along the side edges thereof, said guard adapted to be held against the back of an elongated flat rectangular section file, said guard being of a width approximately double the width of the file for which it is adapted, and said rolled side edges being of a diameter slightly less than the thickness of the file whereby a common plane tangential to said rolled edges lies behind the outer file surface, said central portion being curved crosswise thereof and concave on the side of the rolled edges.

3. A file guard comprising a resilient sheet metal elongated channel section, said channel section having a central portion with rolled edges along the side edges thereof, said guard adapted to be held against the back of an elongated flat rectangular section file, said guard being of a width approximately double the width of the file for which it is adapted, and said rolled side edges being of a diameter slightly less than the thickness of the file whereby a common plane tangential to said rolled edges lies behind the outer file surface, said central portion being curved crosswise thereof and concave on the side of the rolled edges, and said central portion having two rows of perforations extending substantially the length thereof adjacent the rolled edges to provide for the escape of filings.

4. A file guard comprising a resilient sheet metal elongated channel section, said channel section having a central portion with rolled edges along the side edges thereof, said guard adapted to be held against the back of an elongated flat rectangular section file, said guard being of a width approximately double the width of the file for which it is adapted, and said rolled side edges being of a diameter slightly less than the thickness of the file whereby a common plane tangential to said rolled edges lies behind the outer file surface, said central portion having two rows of perforations extending substantially the length thereof adjacent the rolled edges to provide for the escape of filings.

5. A body finishing file comprising a file holder having spaced hand grips connected by a flexible flat strap, adjustable tension means connecting said hand grips laterally disposed with respect to said flat strap for effecting length-

wise curvature thereof, a resilient channel sectioned guard member having rolled edges applied to said strap with the rolled edges extending away from the strap, a rectangular section file of a length applied to the guard member and located between the rolled edges, common means at either end for securing said file guard member, and strap to said spaced hand grips, said rolled edges being of a diameter slightly less than the thickness of said file, and said rolled edges being spaced apart by approximately double the width of said file.

6. A body finishing file comprising a file holder having spaced hand grips connected by a flexible flat strap, adjustable tension means connecting said hand grips laterally disposed with respect to said flat strap for effecting lengthwise curvature thereof, a resilient channel sectioned guard member having rolled edges applied to said strap with the rolled edges extending away from the strap, a rectangular section file of a length applied to the guard member and located between the rolled edges, common threaded fastening means extending into each of said hand grip at either end for securing said file guard member and strap to said spaced hand grips, said rolled edges being of a diameter slightly less than the thickness of said file, said rolled edges being spaced apart by approximately double the width of said file, the central portion of said guard member having residual curvature crosswise thereof to produce a concave surface on the rolled edge side thereof, and said flat strap and file having relatively flat surfaces in engagement with the central portion of said guard member, whereby adjustment in the tension of said threaded fastening means effects a variation in the transverse curvature of said central portion and shifts the common plane tangential to said rolled edges in respect to the outer surface of said file.

7. A body finishing file comprising a file holder having spaced hand grips connected by a flexible flat strap, adjustable tension means connecting said hand grips laterally disposed with respect to said flat strap for effecting lengthwise curvature thereof, a resilient channel sectioned guard member having rolled edges applied to said strap with the rolled edges extending away from the strap, a rectangular section file of a length applied to the guard member and located between the rolled edges, common threaded fastening means extending into each of said hand grips at either end for securing said file guard member and strap to said spaced hand grips, said rolled edges being of a diameter slightly less than the thickness of said file, said rolled edges being spaced apart by approximately double the width of said file, the central portion of said guard member having residual curvature crosswise thereof to produce a concave surface on the rolled edge side thereof, and said flat strap and file having relatively flat surfaces in engagement with the central portion of said guard member, whereby adjustment in the tension of said threaded fastening means effects a variation in the transverse curvature of said central portion and shifts the common plane tangential to said rolled edges in respect to the outer surface of said file, the central portion of said file immediately adjacent the rolled edges thereof having two rows of perforations extending lengthwise of the file to provide for escape of filings.
